UNITED STATES PATENT OFFICE.

SPENCER C. CARY, OF BALDWINS, ASSIGNOR TO WILLIAM H. VANDERBILT,
OF BROOKLYN, NEW YORK.

BOX-STRAP.

SPECIFICATION forming part of Letters Patent No. 441,227, dated November 25, 1890.

Application filed March 19, 1890. Serial No. 344,521. (No model.)

To all whom it may concern:

Be it known that I, SPENCER C. CARY, a citizen of the United States, residing at Baldwins, county of Queens, State of New York, 5 have invented certain new and useful Improvements in Strap-Irons for Boxes, of which the following is a full, clear, and exact description, reference being had to the accompanying drawings, forming part of this specification.

My invention relates to a strap of sheet metal for use in binding the corners of boxes, and also for securing together successively boxes which are piled or placed one upon another; and my invention consists in a metal strap or plate constructed as hereinafter set forth and provided with the devices herein-after specified, whereby the results hereinabove recited are attained.

Figure 1 is a view in perspective of a strap containing my invention. Figs. 2 and 3 are similar views of the same, showing a modification of my invention. Fig. 4 is a similar view of the same, showing a modification of the devices shown in Figs. 2 and 3. Fig. 5 illustrates the application of a strap containing my invention to boxes arranged singly or in tiers; and Fig. 6 is a detail view in section of the fastening devices provided for my strap, 30 taken on line xx , Fig. 3.

A is the strap-iron, composed of a metal band of a desirable length and width. At or near each end of the strap-tongues a are formed by cutting the same from the body of the band and bending them at an angle thereto from one face thereof, as shown. The tongues which are adjacent to the extremities of the strap may advantageously be made somewhat longer than those formed nearest to the middle of the strap-iron, and it is preferable to cut the tongues from the band-body at the opposite ends of the strap with their longitudinal axes at right angles to each other, so that when they are bent at an angle to a face of the strap their planes will be at right angles to each other at the opposite ends of the strap, as shown plainly in Fig. 1.

Each tongue is given a longitudinal corrugation a' , which has a taper corresponding to the taper of the tongues, as shown, and these corrugations begin within the body of the tongue and somewhat back from or above the

base of the tongue, so as to leave a portion of the body of the tongue at its base, where it unites with the band-body, plane-faced and 55 without corrugation. The corrugations desirably extend to and terminate at the point a' of each tongue, as shown.

The strap A is in use bent to substantially a right angle about midway of its length, as 60 illustrated at A' , Fig. 5, with the tongues a on the inner face of the angle-plate thus formed. The tongues may now be driven into the side or top of a box, upon the corner or angle of which the bent strap is placed, as 65 illustrated in Fig. 5, thus serving to bind or re-enforce the box-corners. While the corrugation a' in each tongue serves to stiffen the tongue, so that it may be driven into the wooden wall of the box effectively, the plane-faced neck at the base of each tongue enables the tongue to bend or yield flatwise at 70 its juncture with the band, so as to enter the box-wall more or less diagonally, thus drawing the band snugly to the box-corner, and so 75 as to more or less follow the grain of the wood in being driven into the wall. When the planes of the tongues at the opposite ends of the strap are at right angles to each other, the tongues will, by entering the box-walls in 80 different directions relatively to the grain of the wood at the opposite ends of the strap, be more effectively seated in the box-walls.

In further carrying out my invention I combine with the strap A , having integral with it 85 the described tongues a by said tongues being cut from and bent to project from the strap-body, as set forth, a plate B , extending from the strap-body and adapted to be secured to a surface or object to which it is fitted. This 90 plate B may extend laterally from one edge of the strap, as shown in Fig. 4, and be provided with an aperture b at or near its outer end or side, whereby when the strap is seated upon and attached to a box-wall or other object by its integral tongues a , either flatwise or bent angularly upon itself, the plate B may be attached by a nail or similar device passed through the aperture b to an adjacent object—as, for example, a contiguous box or 95 package—or the plate B may, and preferably should, extend laterally across or between the side edges of the strap and project angularly and desirably at a right angle to that face of

the strap from which the tongues *a* project, as shown in Figs. 2 and 3. The plate *B* is adapted to be attached to a box-wall or other object, and for this purpose is preferably 5 provided with tongues *b'*, cut from its body and bent to project from a face of the plate, as shown.

The strap *A* and plate *B* may be formed integral in one piece by slitting the strap 10 longitudinally from one end to a point more or less near the opposite end and then bending the two parts of the slit portion reversely at right angles to the unslitted end, as shown in Fig. 2, whereby the halves of the 15 slit portion will constitute the strap-body and may have the tongues *a* cut therefrom, as described, and the unslitted portion will constitute the plate *B*, having its tongues *b'*, as shown; or the plate *B* may be constituted by 20 cutting the same on three sides from the body of the plate *A* and bending it at right angles to the strap at its remaining edge, as illustrated in Fig. 3.

The strap and plate shown in Figs. 2 and 25 3 are specially adapted for use in binding together boxes which are arranged one upon another in tiers, as illustrated in Fig. 5. The plate *B* is placed between the opposed faces or walls of two boxes and held in position by 30 means of the tongues *b'* or nails, as the case may be, driven into a box-wall, as shown, and the opposite ends of the strap are secured to the walls, respectively, of the two adjacent boxes. By means of the strap and its plate 35 applied as described to the several adjacent corners of two boxes throughout a tier or tiers of boxes all the boxes in a pile thereof may be secured together, so as to constitute a single package capable of being handled 40 singly. The plates *B* will operate to prevent lateral movement of the boxes one upon another throughout the series, and the strap-bodies will serve to bind the adjacent boxes together throughout said series. The tongues 45 which are formed in the strap-body may be formed only at the strap ends and may be dispensed with at the central portion of the strap, where the angular bend is made therein to fit the strap to a box-corner, or where the 50 plate *B* joins the strap; or in place of said tongues at such central portion of the strap-body apertures *b*² may be formed in the strap for the passage of fastening-nails at such portion of the strap-body.

What I claim as my invention, and desire 55 to secure by Letters Patent, is—

1. A strap-iron for boxes, composed of a metal band provided with tongues cut from the body of the band and bent angularly to a face thereof and corrugations in said tongues 60 extending longitudinally thereof from a point above the base end of said tongues to and terminating at or near the extremity of said tongues, whereby a plane-faced neck is provided on the tongue where it joins the band-body, substantially as and for the purpose set forth.

2. A strap-iron for boxes, composed of a metal band provided with tongues cut from the body of the band between its side edges 70 and bent angularly to a face of the band at each end thereof, with the planes of the tongues at one end of the band at right angles to the planes of the tongues at the other end of the band, substantially as and for the 75 purpose set forth.

3. A strap-iron for boxes, composed of a metal band provided with tongues cut from the body of the band and bent angularly to a face of the band, and a metal plate integral 80 with and projecting from said band, whereby while the band-body may be attached to one or more boxes or objects the plate may be secured to or upon one of the same or a separate box or object substantially as and for 85 the purpose set forth.

4. A strap-iron for boxes, composed of a metal band provided with tongues cut from and turned angularly to a face of the body of the band, and a plate integral with the band 90 and extending therefrom between the side edges thereof, with its plane at an angle to that of the band, substantially as and for the purpose set forth.

5. A strap-iron for boxes, composed of a 95 metal band and a plate integral with, extending laterally across, and projecting from a face of the band, said band on the face thereof from which said plate projects, and said plate being provided with tongues cut, respectively, from the body of said band and plate and bent at an angle thereto, respectively, substantially as and for the purpose set forth.
